CLAIM

The ornamental design for a multifunction massage apparatus, as shown and described.

DESCRIPTION

FIG. 1 is a front perspective view of a multifunction massage apparatus, showing my new design;

FIG. 2 is a front view of the multifunction massage apparatus;

FIG. 3 is a rear view of the multifunction massage apparatus;

FIG. 4 is a left side view of the multifunction massage apparatus;

FIG. 5 is a right side view of the multifunction massage apparatus;

FIG. 6 is a top view of the multifunction massage apparatus;

FIG. 7 is a bottom view of the multifunction massage apparatus; and,

FIG. 8 is a front perspective view of the multifunction massage apparatus, with an attachment strap shown in broken lines.

The broken lines in the drawing form no part of the claimed design.
